US00D688949S

(12) **United States Design Patent**
Johnson et al.

(10) **Patent No.:** **US D688,949 S**
(45) **Date of Patent:** ** *Sep. 3, 2013

(54) **BEVERAGE CONTAINER WITH CAP**(75) Inventors: **Dean L. Johnson**, Littleton, CO (US);
David L. Bonfoey, Thornton, CO (US)(73) Assignee: **Ball Corporation**, Broomfield, CO (US)

(*) Notice: This patent is subject to a terminal disclaimer.

(**) Term: **14 Years**(21) Appl. No.: **29/408,691**(22) Filed: **Dec. 15, 2011****Related U.S. Application Data**

(62) Division of application No. 29/378,146, filed on Oct. 29, 2010, now Pat. No. Des. 678,772.
